UNITED STATES PATENT OFFICE.

JAY G. COUTANT, OF CHICAGO, ILLINOIS, ASSIGNOR TO THE RAILWAY MATERIALS COMPANY, OF CHICAGO, ILLINOIS, A CORPORATION OF ILLINOIS.

APPARATUS FOR CONTROLLING AND CONVEYING PULVERIZED FUEL.

1,195,186.

Specification of Letters Patent. Patented Aug. 22, 1916.

Application filed August 31, 1914. Serial No. 859,355.

To all whom it may concern:

Be it known that I, JAY G. COUTANT, a citizen of the United States, residing at Chicago, in the county of Cook and State 5 of Illinois, have invented certain new and useful Improvements in Apparatus for Controlling and Conveying Pulverized Fuel, of which the following is a specification.

My invention relates in general to the art 10 of burning pulverized solid fuel and more specifically to a controller for feeding such fuel to the furnace in which it is to be burned.

Various types of feeding devices have 15 been suggested all of which, however, are subject to such disadvantages as packing of the fine fuel, clogging of the pipes by large pieces and failure to obtain a uniform mixture of the fuel and the gaseous medium 20 in which it is carried.

It is an object of my invention to provide a controller which will move the pulverized fuel uniformly to the point at which it is delivered to the burner pipe and which will 25 suspend the fuel in a gaseous medium in the form of a fuel cloud before it is drawn by the injector into the burner pipe.

Another object of my invention is the provision of means whereby a plurality of burners 30 may be fed and the supply of pulverized fuel controlled from a central controller which, if desired, may be located at some distance from the burners.

Other objects and advantages of my invention will be apparent as the same is 35 more clearly understood by reference to the following specification when read in connection with the accompanying drawings in which—

Figure 1 is a vertical section through the controller; Fig. 2 is a side elevation showing a plurality of furnaces supplied from a central controller; Fig. 3 is an end elevation of the controller shown in Fig. 2, and Fig. 45 4 is a side elevation showing a slightly different application of my controller to a plurality of furnaces.

On the drawing, 1 indicates a fuel chamber which is preferably made of a flanged 50 section, as shown in Fig. 1, whereby a plu-

rality of chambers may be mounted one above the other, as shown in Fig. 2, and secured together by bolts similar to those shown at 2 in Fig. 1. Where a single fuel chamber is employed a hopper 3 is secured 55 by similar bolts to the upper flange 4. Secured by means of bolts 5 at one end of the fuel chamber is a casing 6 which is provided at one end with a removable plate 7, suitable bolts 8 being used to secure the plate in position. The fuel chamber 1 is provided at the end adjacent the casing 6 with an opening 9 which registers with an opening in the end of the casing. At the opposite end of the fuel chamber a boss 10 is formed integral with the end thereof, said boss being provided with a bearing 11 adapted to support one end of a shaft 12, the other end of which is supported in a bearing 13 mounted in the boss 14, which is integral with the 60 plate 7. Within the fuel chamber 1 the shaft 12 carries a screw conveyer 15 which extends through the opening 9 and into the casing 6. The L-shaped beaters 16 are mounted on the shaft 12 within the fuel 65 chamber 1 and adapted to rotate therewith to continuously stir the pulverized fuel and keep it in a loose condition.

A pipe 17 is secured by means of screw threads or other suitable means in the boss 14 and is connected to a source of a gaseous medium such as air (not shown). Within the casing 6 the shaft 12 is hollow, as indicated at 18, and a plurality of holes 19 extend through the shaft to admit the gaseous 80 medium. A flanged end plate 20 is removably secured to the shaft 12 at one end of the casing 6 by means of a bolt 21 and the plate 20 supports a frusto-conical screen 22 which extends within the casing to a point 85 near the opening 9, a suitable frame being provided for strengthening the screen 22. A pipe 23 is connected to the casing 6 beneath the screen 22 and this pipe in turn is connected by suitable means to the burner 90 pipe 24, an injector 25 being provided at the point of juncture, the latter connected with a source of gas such as air under pressure and adapted to draw the fuel cloud which 95 results from the operation of my device into 100

the burner pipe 24. The shaft 12 is adapted to be driven from any source of power.

The operation of my device is as follows: Finely pulverized solid fuel is supplied to the hopper 3 and passes therefrom into the fuel chamber 1 where it is kept in a loose condition by the revolving beaters 16. The pulverized material is continuously removed from the fuel chamber 1 by the conveyer 15 and is carried into the screen 22 which is fixed to the shaft 12 and revolves therewith. A gaseous medium is continuously supplied through the pipe 17 and emerging through the holes 19 mixes thoroughly with the pulverized fuel and passes therewith through the screen 22, the material falling in the form of a fuel cloud into the pipe 23 whence it is drawn by the injector 25 into the burner pipe 24.

20 The screen 22 is of sufficient fineness to prevent the passage of any of the fuel that has not been reduced to a fineness sufficient to allow the same to be readily carried by the current of gas. Any material which is 25 too large to pass the screen is retained therein and may be removed from time to time by dismounting the screen 22 which may be readily accomplished by removing the plate 7 and the bolt 21. The screen 22 has an additional function of separating particles of fuel so that they, when mixed with the gaseous medium from the pipe 17, readily 30 form a fuel cloud with the solid particles held in suspension. This obviates all clogging 35 of the burner pipes which is a common defect in previous controlling devices for the reason that the fuel is delivered to the burner pipe in suspension and can not possibly collect therein to form a stoppage.

40 In Fig. 2 I have shown the application of my controllers to a plurality of furnaces 26. The fuel chambers 1 are here shown as connected one above the other with a hopper 3 mounted on the uppermost chamber. 45 Each of the chambers is provided with a casting 6 and operating mechanism therein so that each forms a separate and distinct unit, all of the units being fed, however, from a single hopper. From the casings 6 separate pipes 23 lead, as shown in Fig. 3, to 50 separate injectors which draw the pulverized fuel into individual burner pipes 24. By this arrangement I am enabled to feed and control a plurality of furnaces from a single feed controller which may be located at a considerable distance from the furnace. 55 While the control is centralized in this application of my invention the feed to each of the furnaces may be readily varied at will 60 owing to the fact that each furnace is provided with a distinct controlling device.

In Fig. 4 I show another application of my invention in which a plurality of furnaces 26 are connected to a single controller

which is supplied from a hopper 3. The controller is identical with that previously described and the pipe 23 leading therefrom is connected through an injector with a burner pipe 24 from which branch pipes 27 lead to the respective furnaces 26. As all 70 of the fuel which passes through the pipe 24 is not necessarily burned in the furnaces I provide a return pipe 28 which is connected to a suitable separating means, such as a cyclone separator 29, in which the 75 particles of fuel are separated from the gaseous medium and the former are returned to the hopper 3. By this arrangement I am enabled to feed a plurality of furnaces from a central controller which 80 is provided with a single fuel chamber, thereby reducing the amount of mechanism necessary to accomplish the desired result.

It is thought the invention will be understood without further explanation and it 85 will be apparent that I have succeeded in perfecting a controller and a means of applying the same which obviates many of the objectional features which are inherent in the structures previously used for this purpose. With my controller it is possible to obtain such a uniform mixture of the pulverized fuel with the carrier gas that the mixture is extremely mobile and does not settle in the conveying pipes to clog the 95 same. Moreover, by the arrangements indicated in Figs. 2 to 4 it is possible to establish a central control station and to control the firing of all of the furnaces therein in some of which may be at a considerable 100 distance from this central station. This is an extremely desirable feature since much of the objection to the use of pulverized fuel from practical shop men has been due to the necessity of installing complicated 105 controlling apparatus adjacent each furnace to be used.

It will be obvious that various changes may be made in the form, construction and arrangement of the parts without departing 110 from the spirit and scope of the invention or sacrificing any of its material advantages, the form hereinbefore described being merely a preferred embodiment thereof.

I claim:

1. In a controller for conveying finely pulverized fuel to a burner therefor, the combination of a fuel chamber, means extending from said chamber to continuously convey fuel therefrom, a rotary frusto-conical screen surrounding the extension of said conveying means outside said chamber to receive and separate the fuel particles, whereby they are uniformly mixed with a gaseous medium and to retain the coarser 120 particles, and means to convey the mixture to said burner.

2. In a controller for conveying finely

- pulverized fuel to a burner therefor, the combination of a fuel chamber, means extending from said chamber to continuously convey fuel therefrom, a rotatable screen to said fuel, whereby said fuel particles are 65 thoroughly mixed therewith to form a fuel cloud, and means for conveying said fuel cloud to said burner.
5. In a controller for feeding finely pulverized solid fuel to a burner therefor, the combination of a fuel chamber, means for continuously conveying fuel from said chamber, a rotary screen for separating fuel particles, means within the screen for supplying and mixing a gaseous medium with 70 said particles to form a fuel cloud, and means for conveying said fuel cloud to said burner.
10. In a controller for feeding finely pulverized solid fuel to a burner therefor, the combination of a fuel chamber, means for continuously conveying fuel from said chamber, a rotary screen for separating fuel particles, means within the screen for supplying and mixing a gaseous medium with 75 said particles to form a fuel cloud, and means for conveying said fuel cloud to said burner.
15. In a controller for feeding finely pulverized solid fuel to a burner therefor, the combination of a fuel chamber, means for continuously conveying fuel from said chamber, a rotary screen for separating fuel particles, means within the screen for supplying and mixing a gaseous medium with 80 said particles to form a fuel cloud, and means for conveying said fuel cloud to said burner.
20. In a controller for feeding finely pulverized solid fuel to a burner therefor, the combination of a fuel chamber, means for continuously conveying fuel from said chamber, a rotary screen for separating fuel particles, means within the screen for supplying and mixing a gaseous medium with 85 said particles to form a fuel cloud, and means for conveying said fuel cloud to said burner.
25. In a controller for feeding finely pulverized solid fuel to a burner therefor, the combination of a fuel chamber, means for continuously conveying fuel from said chamber, a rotary frusto-conical screen for separating fuel particles, means within the screen for supplying and mixing a gaseous medium with 90 said particles to form a fuel cloud, and means for conveying said fuel cloud to said burner.
30. In a controller for feeding finely pulverized solid fuel to a burner therefor, the combination of a fuel chamber, a screw conveyer extending from said chamber for continuously conveying fuel therefrom, means surrounding said conveyer outside said chamber for separating the fuel particles, means within said separating means for supplying a gaseous medium to said particles to form a fuel cloud, and means for conveying said fuel cloud to said burner.
35. In a controller for feeding finely pulverized solid fuel to a burner therefor, the combination of a fuel chamber, a screw conveyer extending from said chamber for continuously conveying fuel therefrom, means surrounding said conveyer outside said chamber for separating the fuel particles, means within said separating means for supplying a gaseous medium to said particles to form a fuel cloud, and means for conveying said fuel cloud to said burner.
40. In a controller for feeding finely pulverized solid fuel to a burner therefor, the combination of a fuel chamber, a screw conveyer extending from said chamber for continuously conveying fuel therefrom, means surrounding said conveyer outside said chamber for separating the fuel particles, means within said separating means for supplying a gaseous medium to said particles to form a fuel cloud, and means for conveying said fuel cloud to said burner.
45. In a controller for feeding finely pulverized solid fuel to a burner therefor, the combination of a fuel chamber, a shaft mounted therein, means within the chamber for continuously conveying fuel from said chamber, a rotary frusto-conical screen for separating fuel particles, means within the screen for supplying and mixing a gaseous medium with 100 said particles to form a fuel cloud, and means for conveying said fuel cloud to said burner.
50. In a controller for feeding finely pulverized solid fuel to a burner therefor, the combination of a fuel chamber, a shaft mounted therein, means within the chamber for continuously conveying fuel from said chamber, a rotary frusto-conical screen for separating fuel particles, means within the screen for supplying and mixing a gaseous medium with 105 said particles to form a fuel cloud, and means for conveying said fuel cloud to said burner.
55. In a controller for feeding finely pulverized solid fuel to a burner therefor, the combination of a fuel chamber, a shaft mounted therein carrying a screw conveyer for continuously removing fuel therefrom, means surrounding said shaft exteriorly of said fuel chamber for separating the fuel particles, the end of said shaft within said separating means being hollow and provided with openings to admit a gaseous medium 110 to said fuel, whereby said fuel particles are thoroughly mixed therewith to form a fuel cloud, and means for conveying said fuel cloud to said burner.
60. In a controller for feeding finely pulverized solid fuel to a burner therefor, the combination of a fuel chamber, a shaft mounted therein carrying a screw conveyer for continuously removing fuel therefrom, means surrounding said shaft exteriorly of said fuel chamber for separating the fuel particles, the end of said shaft within said separating means being hollow and provided with openings to admit a gaseous medium 115 to said fuel, whereby said fuel particles are thoroughly mixed therewith to form a fuel cloud, and means for conveying said fuel cloud to said burner.
65. In a controller for feeding finely pulverized solid fuel to a burner therefor, the combination of a fuel chamber, a shaft mounted therein, means within the chamber for continuously conveying fuel from said chamber, a rotatable frusto-conical screen removably mounted adjacent said chamber and fed by said conveyer, the end of said screen opposite said conveyer being closed, and a casing for said screen having a removable cover 120 adjacent the closed end of said screen, whereby the casing may be opened and the screen removed from time to time to clear the same of an accumulation of fuel particles too large to pass therethrough.
70. In a controller for feeding finely pulverized solid fuel to a plurality of burners therefor, the combination of a series of individual

fuel chambers arranged one above the other, common means for supplying said chambers with fuel, means in each of said chambers for continuously conveying the fuel therefrom, means for separating the fuel particles and uniformly mixing them with a gaseous medium to form a fuel cloud, and means for conveying said fuel cloud to said burners.
